UNITED STATES PATENT OFFICE.

WILLIAM C. HENDERSON, OF BUDU, MISSISSIPPI.

OFFSETTING MECHANISM.

Application filed June 14, 1922. Serial No. 568,172.

To all whom it may concern:

Be it known that WILLIAM C. HENDERSON, a citizen of the United States of America, residing at Bude, in the county of Franklin 5 and State of Mississippi, has invented new and useful Improvements in Offsetting Mechanisms, of which the following is a specification.

The object of the invention is to provide 10 a simple and efficient offsetting mechanism for saw mill carriages and similar structures as a means of providing for the return of the carriage in a path sufficiently offset from that pursued in its forward movement 15 to avoid a drag of the saw on the cut surface of the log or of the timber; and with this object in view the invention consists in a construction and combination of parts of which a preferred embodiment is shown in 20 the accompanying drawings, wherein:—

Figure 1 is a plan view partly broken away of an off-setting mechanism embodying the invention applied in the operative position to a saw mill carriage.

25 Figure 2 is a transverse section on the plane indicated by the line 2—2 of Figure 1.

Figure 3 is a section on the plane indicated by the line 3—3 of Figure 1.

Figure 4 is a detail view of the shoe.

30 Figure 5 is a similar view of the bell-crank lever.

Figure 6 is a similar view of the rocker by which connection is made with the rock shaft.

35 Figures 7 and 8 are similar views respectively of the yoke and collar by which connection is made between the rock shaft and the wheel spindles.

A conventional form of carriage is indicated at 10 provided with the front and 40 rear rollers 11 and 12 of which the former are peripherally grooved as in the ordinary practice for traversing a V-guide bar or rail, said wheels being carried by spindles 13 extending transversely of the path of movement of the carriage with the bearings 14 of the latter adapted for movement longitudinally of the spindles to permit of a forward and rearward movement of the carriage relative to the wheels.

50 Disposed longitudinally of the carriage or parallel with the path of operative movement thereof, and mounted in suitable bearings 15 on the carriage is a rock shaft 16 provided near its extremities with yokes 17, each of which is provided with a sleeve 18

keyed to the rock shaft and having radial arms 19 carrying pins 20 which are terminally headed as shown at 21 to engage seats 22 in a collar 23 which is secured to the adjacent wheel spindle between retaining rings 24 which may be held in place by set screws or any equivalent means. The collar 23 is preferably split to facilitate its application to the spindle and therefore the 60 rings 24 may be fastened upon or formed integral with the spindle and as the rock shaft is mounted in bearings secured to the carriage it is obvious that a rocking movement of the shaft will cause a forward and 65 rearward movement of the carriage relative to the spindles of the supporting wheels. The pins 20 are preferably threaded and extend through suitable openings in the arms 70 75 19 and are engaged by suitable nuts 25 to provide for relative adjustment.

A shoe 26 is arranged with a channeled bearing edge 27 to traverse the forward guide bar or track and exert a slight frictional resistance by reason of such contact, the same 80 having a limited movement longitudinally and independently of the carriage determined by upstanding fingers 28 operating in keepers 29 which are elongated in a direction parallel with the path of the carriage and carried by a keeper plate 30 secured to the carriage, so that as the carriage reverses its direction of movement at the ends of its 85 forward and rearward strokes the resistance between the shoe and the guide serves to hold the shoe stationary while the carriage moves independently thereof for a distance determined by the length of the keepers.

Also mounted upon the carriage at a pivotal point 31 is a bell-crank lever 32 having connection with the shoe at one end and having connection at the other end with the rock shaft so that the independent movement of the shoe relative to the carriage serves to actuate the bell-crank lever and thereby communicate a limited rocking movement to the shaft 16 to thereby shift the carriage rearwardly or forwardly according to the direction of movement of the carriage in its path. The connection illustrated in the drawings between the bell-crank lever and the shoe consists of a pin 33 arranged in spanning relation with a slot 34 in the shoe for engagement by a notch 35 in the end of the transverse arm of the bell-crank lever, and the connection between the other or the longitudinal arm of said 90 95 100 105 110 115

lever and the rock shaft consists of a rocker 36 carried by the rock shaft and a link 37 extending from an arm 38 of the rocker to said longitudinal arm 32^a of the bell-crank lever. In practice it is preferred to provide the link with a means of adjustment such as the turn buckle 39 so that a relative adjustment of the rock shaft angularly with respect to the bell-crank lever may be effected to insure a proper and sufficient movement of the carriage with relation to the spindles of the bearing rolls. The rocker 36 in addition to the arm 38 includes a sleeve 40 which is keyed to the shaft, and the bell-crank lever is mounted upon a plate 41 from which extends the stud 31 forming the fulcrum of said lever.

In operation, as will be obvious, the transverse movement of the carriage due to the drag of the shoe and the communication of motion through the bell-crank lever to the rock shaft will occur at each end of the longitudinal path of movement of the carriage, so as to offset the saw or other tool from its operative path of movement during the return stroke of the carriage, and owing to the means herein set forth for accomplishing this movement it will be obvious that it may be effected with a minimum of added

load in the operation of the mechanism 30 while insuring a reliability in action which is desirable in connection with mechanisms of this type.

Having described the invention, what is claimed as new and useful is:—

An offsetting mechanism for a roller supported carriage having a longitudinally disposed rock shaft provided with means for effecting a transverse movement of the carriage with reference to its supporting roller, 40 a drag for traversing and frictionally engaging one of the guides of the carriage, and spaced keepers mounted on the side of the carriage and elongated in the direction of the length of the carriage, the drag having fingers engageable in said keepers and movable longitudinally thereof, and a bell crank lever pivoted on the under side of the carriage and having an operative connection with the rock shaft comprising a 50 link connected with the shorter arm of the bell crank lever, the longer arm of said bell crank lever having a slot and pin connection with the drag.

In testimony whereof he affixes his signature. 55

WILLIAM C. HENDERSON.
